UNITED STATES PATENT OFFICE.

SAMUEL M. PARK, OF CHICAGO, ILLINOIS.

ASSORTING-MACHINE.

SPECIFICATION forming part of Letters Patent No. 283,414, dated August 21, 1883.

Application filed December 8, 1882. (No model.)

To all whom it may concern:

Be it known that I, SAMUEL M. PARK, a resident of the city of Chicago, county of Cook, State of Illinois, have invented certain new and useful Improvements in Assorting-Machines, of which the following is hereby declared to be a full, clear, and exact description, sufficient to enable others skilled in the art to which said improvements most nearly appertain to make, construct, and use the same, reference being had to the accompanying drawings, wherein—

Figure 1 is a view in side elevation of the improved machine, a portion of the frame being broken away to exhibit certain of the parts in section. Fig. 2 is a view in side elevation of a modified form of the machine, a portion of the side frame being broken away to better show in section the relation of certain of the parts. Figs. 3, 4, 5 are detail views of various kinds of separating device which may be used in the machine.

The invention relates to machines for assorting a promiscuous heap of feathers, bristles, lath, paper strips, or the like into several groups or distinct portions, having the feathers, &c., in each particular group of substantially the same length, so that after being passed through the machine the feathers, &c., will be assembled in several portions, according to their respective size, and be in condition most convenient for manipulation in manufacture of brushes or brooms, &c., as the case may be, dependent upon the nature of the material assorted.

The invention relates particularly to improvements in assorting-machines of the kind described and shown in Letters Patent No. 254,234, granted and issued to me, and bearing date the 28th day of February, A. D. 1882; and it consists in certain improvements in the construction thereof, all as hereinafter described, and distinctly defined in claims following.

As is more fully described in said patent, the rectangular frame A has a series of rolls, *a*, mounted transversely therein in substantially horizontal planes, these rolls being free to revolve in suitable bearings in the frame, and carrying on the extended ends of their axles driving-pulleys *b*, which are connected up by

endless belts, so that all of the rolls may be rotated, and in the same direction, from a common source of power or line-shaft. The rolls *a* are set in the frame at gradually-increasing distance apart, these differences in distance corresponding to the difference in size or length of the various groups of feathers, &c., into which it is desired to assort the heap. Immediately above the rolls *a* is preferably arranged a companion series of rolls, *a'*, of like diameter therewith, mounted in bearings of frame A, so as to revolve freely and in direction opposite to the rolls *a*, through medium of gear-wheels *c c'*, which are secured to the extended ends of the axles of the rolls. Guide-plates B are fitted in the rectangular frame of the machine, which plates, as shown, are practically in even plane immediately above the bite of the sets of rolls *a a'*, and extend from set to set, so as to nearly come in contact therewith. Experience has shown that unless the guide-plates are made to span the space entirely between the roll-sets the natural tendency of the rolls, in revolving, to throw the feather, &c., out of and above the plane of feed will cause the feather at times to be projected over the guide and away from the action of the machine. Hence it is important that the guides be arranged substantially as shown to prevent any such irregularity in operation. Again, it will be noted that the lower rolls, *a*, are provided with slight grooves or indentations in their surface, which, when feathers are being assorted, serve to seat the rib of the feather to prevent its turning, and to position it, so that the feather shall pass straight and evenly through the machine. As the feather is fed into the bite of the first set of rolls, *a a'*, the rib takes into the groove of roll *a*, holding the feather steady, so that the plume or vane will be held securely in the bite and the feather evenly advanced by rotation of the rolls. As the tip of the feather emerges it turns slightly upward and bears against the guide-plate B, which acts to steady the feather, so that it will pass directly and in an approximately straight line toward and into the bite of the next set of rolls, by which co-operation of the guides it is evident that the measurement of the feathers and their consequent dis- 100

tribution according to size is rendered more accurate. If the feather be too short to span the space between succeeding sets of rolls, it drops down into the bin or compartment beneath arranged conveniently to receive it, and when a sufficient number thus assorted has accumulated the feathers are removed and bunched for future use.

It is plain that in a machine thus constructed the lower set of rolls, placed at varying distance apart, is the efficient means for effecting the desired separation, the upper set of rolls and the guides operating in conjunction to present a continuous flat surface practically tangent to the plane of the lower set, and coacting with said lower set, first, to advance the feathers by the bite of the rolls thereon, and, second, to secure the accurate admeasurement thereof as they pass from bite to bite. The upper series of rolls may have the gear-wheels c' omitted, if preferred, in which event they will move merely by frictional contact with the passing feather; or, instead of having the upper series of rolls, it is an obvious modification that these may be entirely omitted and a continuous plane-guide extending from end to end of the machine be used, although the results thereby attained are not so satisfactory as when the machine is constructed after the manner heretofore detailed. Such continuous plane-guide may consist of a movable endless belt, as illustrated in Fig. 2 of drawings, said belt D passing over rollers d , mounted transversely in proper bearings near the ends of the machine, and having preferably the gear-wheels d' on their axles to mesh with like wheels c of the rolls a , so as to partake of like motion therewith. The operation of such endless belt will be essentially the same as that of the guides and rolls heretofore detailed, and need not be more fully set out. When the endless belt is employed, the intermediate rolls of the lower series may be left free to rotate by frictional contact with the passing feather, &c., or else may be fixed, and may have the form of a rounded quarter section, as at a^2 , Figs. 2 and 4, or a straight strip, as at a^3 , Figs. 2 and 3.

It is generally desirable that the lower rolls, or their equivalents, as described, be provided with cross-grooves or serrations in their faces next in contact with the feather to more certainly position the feather in its passage; but approximately good results may be obtained if such be modified or entirely omitted.

For convenience of observation the guides B are usually made of glass; but this is not necessary, for any material suitable to the purpose may be used, the single precaution being taken to have the face of the guides of the frame, &c., quite smooth, so as to avoid any obstruction to the free and uninterrupted progress of the feather, &c.

Other modifications may be made in the machine as herein described without departing from the spirit of the invention. Thus in lieu of the flat guide B , a series of parallel wires may approximately span the space between the sets of rolls, said wires being at such distance apart as to admit the feather-tip between them, which said tip will thereby be held from turning and the feather be caused to pass in direct line from bite to bite. Parallel ridges corresponding in character to said wires may be likewise formed on the surface of the endless-belt guide, and with like effect.

At the front of the machine there may be a set of three rolls, E , of relative diameter and direction of rotation, as shown, these rolls serving to bend the feather permanently as it passes therethrough toward the first set of rolls of the assorter, so that in subsequent stages of its progress it will turn upward and impinge against the guides; thus insuring certainty in its feed. This is of much importance where the passing feather is from the tail of the fowl and has its rib split, since such feathers have naturally a tendency to droop at the tip, which tendency needs to be counteracted.

Having thus described the invention, what I claim as new, and desire to secure by Letters Patent, is—

1. In an assorting-machine, the combination, with the series of rolls or equivalents, arranged at varying distance apart, of the horizontal guide mechanism located above the same, substantially as described

2. In an assorting-machine, the combination, with a horizontal guide, of mechanism for advancing the materials to be assorted longitudinally of the machine, substantially as described.

3. An assorting-machine the separating devices of which are grooved or serrated and are arranged transversely to the path of the material being assorted, substantially as described.

4. In an assorting-machine, the combination, with the separating-rolls arranged at varying distance apart, of the horizontal guide extending essentially from roll to roll, substantially as described.

5. In an assorting-machine, the combination, with the separating-rolls arranged at varying distance apart, of the horizontal guides and rolls located in an essentially continuous plane above the same, substantially as described.

In testimony whereof I have hereunto set my hand this 6th day of December, A. D. 1882.

SAMUEL M. PARK.
